J. Casey.
Window Frame.

No 15,000.

Patented July 3, 1856.

UNITED STATES PATENT OFFICE.

JOHN CASEY, OF NEW YORK, N. Y.

WINDOW-FRAME.

Specification of Letters Patent No. 15,000, dated June 3, 1856.

To all whom it may concern:

Be it known that I, JOHN CASEY, of the city, county, and State of New York, have invented a new and useful Improvement in 5 Window-Frames, whereby the Sashes May be Detached Therefrom Without Removing the Beads from the Frames; and I do hereby declare that the following is a full, clear, and exact description of the same, reference 10 being had to the annexed drawings, making a part of this specification, in which—

Figure 1, is a face view of a window frame one side of which is bisected and showing my improvement. Fig. 2, is a transverse 15 section of ditto (x) (x) Fig. 1 showing the plane of section. Fig. 3, is a horizontal section of ditto (y) (y) Fig. 1, showing the plane of section.

Similar letters of reference indicate 20 responding parts in the several figures.

My invention consists in having a portion of one of the side pieces or stiles of the frame or casing movable and arranged so will be presently shown and described so 25 that both sashes may be removed from the frame or casing without detaching the beads therefrom.

To enable those skilled in the art to fully understand and construct my invention, I 30 will proceed to describe it.

A represents a window frame or casing having pockets at each side of it to receive sash weights which are attached to the sashes B B by cords (a). The cords are attached 35 to the sashes by having knots or balls (b) on their ends, said knots or balls being fitted in slots or grooves (c) in the upper part of each sash at each side. The cords (a) work over pulleys (d) in the upper ends of the stiles 40 or side pieces (e) (f) of the frame or casing. The stiles or side pieces (e) (f) of the frame or casing have the usual parting bead (g) fitted in them to form the grooves, one for each sash, one of the stiles (e) has 45 a section of it C, made detached from the other part, the section or part C extends some distance above the lower sash B and it embraces a portion of the parting bead (g) the part C does not extend entirely 50 across the stile but merely takes in the parting bead, the part C is so arranged that it may be shoved bodily back within the socket by having curved slots (h) made in

its upper and lower sides in which lugs (i) attached to the stile fits so that when the 55 part C is shoved back within the pocket it may, when relieved of the pressure or force which attached it return in proper place by its own gravity.

When the part C of the stile is in proper 60 position or flush with the other part, the two sashes may be raised and lowered as usual the operation being precisely the same as the ordinary windows, the sashes of which are provided with weights. 65

In order to detach the sashes from the frame or casing all that is required is to press the lower sash B laterally or sidewise so that the side of the sash will press inward the part C of the stile. By doing this the 70 opposite side of the sash may be brought out free from the bead on the opposite stile and the lower sash will be consequently detached from the frame or casing, the cords 75 (a) are then detached from the sash by withdrawing the knots or balls (a) from the grooves or slots (c) said knots or balls being then fitted in grooves or slots (j) in the stiles (e) (f) so that the weights may be retained, see red lines Figs. 1 and 2. 80 To detach the upper sash B', it is brought down to the lower part of the frame or casing the part C presses back by the hand and the sash is then removed or detached in the same way as the lower sash just described. 85

The above invention is extremely simple and allows the sashes to be detached from the frame or casing with the greatest facility so that in case of washing, glazing, 90 or painting, the work may be done conveniently and better done than if the sashes were in the frames or casing.

Window frames or casings as at present constructed do not allow the sashes to be 95 readily removed from them, the beads require to be taken off, and this is attended with considerable trouble, so much so, that the sashes are rarely removed from the frames while the work above mentioned is 100 performed.

I do not claim having a portion of one of the stiles made adjustable or movable irrespective of the arrangement of the same, or the manner in which said portion is 105 operated; but

What I do claim as new and desire to secure by Letters Patent, is,

Having the portion, C, of one of the stiles, (e), of the casing provided with 5 curved slots, (h), at its upper and lower ends, and having lugs, (i), which are attached to the stile fit in the slots, (h),

whereby the part or portion, C, is rendered adjustable, as shown, for the purpose specified.

JOHN CASEY.
